UNITED STATES PATENT OFFICE.

CHARLES MARTIN BAGSHAW, OF LEICESTER, ENGLAND.

PULLING-OVER MACHINE.

Application filed October 18, 1924, Serial No. 744,336, and in Great Britain October 30, 1923.

This invention has reference to improvements in and relating to pulling-over machines of the type in which the toe and side pincers are carried by rocking-frames to 5 which, after the pincers have put the desired tension on the upper, rocking movement is imparted whereby the pincers are moved so as to lay the marginal portion of the upper against the sole of the last (or the insole on the 10 last), tack supplying and driving means being simultaneously brought into appropriate positions whereby the upper is secured in pulled-over condition on the last. After the pincers have automatically been made to release 15 the upper and the upper has been secured in pulled-over condition on the last, the parts are automatically returned to their initial positions ready for operating on another shoe. A constructional form of the aforesaid type 20 of pulling-over machine is described in the specification of British Letters Patent No. 3,876/14 and in British Patent No. 164,777.

An important object of my present invention is an improved pincers supporting and 25 controlling means that possesses important practical advantages hereinafter pointed out.

My invention is illustrated in the accompanying drawings as applied to one of the usual several pairs of pincers of a pulling-over machine, in which drawings Fig. 1 is a 30 side elevation showing one pair of side pincers and their supporting and controlling means in the initial or starting position with the marginal portion of the upper inserted. Fig. 2 is a similar view with the parts in the 35 position after the pincers have put tension on the upper; and Fig. 3 is a similar view with the parts in the position after the marginal portion of the upper has been laid under the edge of the last and secured in lasted condition.

In said drawings the numeral 6 indicates the 40 rocking-frame which is provided with trunnions as at 7 that are supported in bearings such as 5, carried by the main frame of the machine. The rocking-frame is provided with a tack-receiving pocket 8 closed at its lower end by the tack driver 9 which is mounted on a vertically slidable bar 10 to which, 45 through a thrust rod 11, upward movement is imparted at the appropriate time to drive the tack whereby the upper is secured in pulled-over condition. The tacks are supplied from the usual tack drums (not shown) 50 through flexible tubes 12 connected up with a

tack-passage 13 in a spring-pressed clamping plate 14 (Fig. 3), the said tack-passage and pocket being in communication when the rocking-frame is in its initial or starting position. The last 4 is carried on a support 15. After 60 the upper 3 has been tensioned, as will be described, the rocking-frame 6 is swung on its trunnions 7 to bring the marginal portion of the upper under the edge of the last (at the appropriate time the upper will be released by 65 the pincers as will be described) and the upper will be held against springing back when the pincers have released it by the clamping plate 14 (Fig. 3). When the upper has been secured, the parts are automatically returned 70 to their normal or starting positions. The foregoing is a brief description of the operation of the machine and a detailed description of the mechanism (which forms no part 75 of the present invention) may be had from the specifications of the patents referred to. The said prior specifications also clearly describe and illustrate three sets of pincers, one for the extreme toe and the other two for the sides of the last at or near the tip line and as the arrangement of the three sets of pincers will be similar in carrying out my present invention it will suffice if I illustrate my invention as 80 applied to one pair of pincers, it being understood that my invention is to be applied to all 85 the pincers.

In accordance with my invention the pincers 17 are pivotally carried at 18 by a comparatively long arm 19 that in turn is pivotally carried at 20 by the rocking-frame 6. Said 90 arm has a lug 21 to which one end of a strong spring 22 is attached, the other end of the spring being attached to a pin 23 on the rocking-frame 6. Said spring acts normally to maintain the free or pincers carrying end of 95 the arm 19 in its raised position, an adjustable stop 24 being provided to permit regulation of this. A spring 25 tends to open the pincers.

The depending shanks 26 of the pincers 100 jaws are shaped so that a roll 27 may be received between them, the extreme ends converging so that, if the roll 27 be moved downwardly with respect to the pivot 18, the pincers jaws will be closed, and the dimensions of the parts are such that the said extreme ends will prevent the roll 27 disconnecting from the pincers even when the pincers jaws are closed together without the presence between them 105 of the marginal portion of the upper. 110

The roll 27 is carried by a tension rod 28 that is connected—preferably through a spring cushion in the known manner—to any known suitable either power or manually operated means whereby tension is to be applied to the upper.

The arm 19 is provided with a lug or lugs 29 carrying a pivot pin 30 on which is mounted a rocking bar 31. One end of said rocking bar extends through a slot 32 in the tension rod 28, and the other end is connected by a link 33 to one end of an actuating bar 34, pivoted on a pivot pin 35 on the rocking frame, and the other end of which rests on 15 and extends beyond a block 36 that carries the trunnions 7 referred to.

Adapted to engage the extending end of the actuating bar 34 is a vertically movable plunger 37 which is normally in the position 20 about as shown in Figs. 1 and 2 but which is raised by a cam or other moving part of the machine at the appropriate time so as to lift the extending end of the actuating bar 34, about as shown in Fig. 3.

The parts described serve in the first instance to close the pincers so as firmly to grip the previously inserted marginal portion of the upper, than to move them to put tension on the upper, and, at the appropriate moment, 30 e. g., when the upper (previously pulled over the last) is held firmly against the corner of the last by the clamping-plate 14, to cause the pincers to release their hold on the upper (without allowing the pincers to rise until 35 all the parts of the machine are returned to their normal position).

The operation of my improved pincers closing and opening means is as follows:—

In Fig. 1 the pincers 17 are in the raised 40 position ready to receive the marginal portion of the upper 3. When tension is applied to the tension rod 28, the roll 27 will be moved downwards relatively to the pivot 18. The said pivot, and consequently the pincers 17 45 also, are maintained in their raised position by reason of the tension of the spring 22 acting on the pincers carrying arm 19, until the pincers are closed and more or less firmly grip the marginal portion of the upper. After 50 this, continued downward movement of the tension rod will cause the pincers to follow, the pincers carrying arm 19 swinging about its pivot 20, and thus put tension on the upper. The position of the pincers and related 55 parts when tension has been put on the upper, is shown in Fig. 2, where it will be seen that the rocking bar 31 has moved down with the arm 19 and has maintained its position of substantial parallelism with said bar.

After this the rocking-frame will be swung 60 in the direction to place the marginal portion of the upper under the edge of the last (as described in the prior specifications referred to) and when the clamping-plate 14 firmly 65 presses the upper against the corner of the

last, the plunger 37 is raised, and this will rock the actuating bar 34 about its pivot 35. Owing to the link connection 33, the aforesaid movement of the actuating bar will bring about a rocking movement of the rocking bar 31 on its pivot 30 and, utilizing said pivot as a fulcrum, will cause the free end of the rocking bar to engage against the upper end of the slot 32 in the tension rod 28 and lift said rod whilst the arm 19 and consequently 70 the pincers 17 remain in situ. By this upward movement of the tension rod 28, and consequently of the roll 27 relatively with respect to the converging ends of the pincers shanks, the pincers will be free to be opened 75 by their spring 25.

It is to be observed that at no time is the tension rod 28 with its roll 27 disconnected from the pincers.

As already stated, each pair of pincers will 80 be constructed and provided with the improved actuating and controlling mechanism described, and, as the extending end of each actuating bar such as 34 will project over the plunger 37, all the pincers will be released 85 simultaneously or practically so.

What I claim is:—

1. In a pulling-over machine, a pincers-carrying arm, pincers carried thereby, means to actuate the arm and close the pincers, and a rocking bar pivoted to said arm and engageable with said means to cause the pincers to release its grip on the work.

2. In a pulling-over machine, a pincers-carrying arm, pincers carried thereby, means to actuate the arm and close the pincers, a rocking arm pivoted to the arm and engageable with said means, a pivotally supported actuating bar connected up with said rocking bar and by its movement shifting the rocking bar to cause release of the pincers, and means to actuate the actuating bar.

3. In a pulling-over machine, a pincers-carrying arm, pincers carried thereby, a tension rod for closing the pincers, a rocking bar pivoted to said arm and operatively connected to said rod, and means to rock said rocking bar thereby to release the grip of the pincers.

4. In a pulling-over machine, a pincers-carrying arm, pincers pivotally supported by said arm and having converging shanks, a roll between said shanks, means to cause the roll to act on said shanks thereby to close the pincers, a rocking bar carried by said arm and operatively connected up with said roll, and means to actuate the rocking bar thereby to shift the roll into a position to release the grip of the pincers on the work.

5. In a pulling-over machine, a pincers carrying arm, means to normally hold said arm in raised position, pincers carried by said arm and having converging shanks, a tension rod having a slot and carrying a roll that is engaged between said shanks, a rock-

- ing frame to which said arm is pivoted, a pair of rocking bars, one pivotally mounted on said arm and one end of which engages the slot in the tension rod and the other of which is pivotally mounted on said rocking frame, a link connecting said bars, and a vertically movable plunger to actuate the bars, all for the purpose described.
6. In a machine of the class described, a pivoted pincers support, pincers carried by the free end of said support, means normally holding said free end and the pincers in raised position, a member permanently operatively connected to the pincers but movable relatively thereto for closing the pincers and allowing them to be released, a rocking bar carried by said support and engaging said member for releasing the pincers, and means to rock said bar.
7. In a machine of the class described, a rocking frame, a lever pivotally mounted on said frame, pincers carried by the free end of said lever, means normally holding the lever and pincers in raised position, a slotted member operatively connected with said pincers and having a limited movement relatively thereto, the initial downward movements of said member closing the pincers and continued downward movement giving a pulling movement to the pincers, a rocking lever mounted on the pivoted lever and engaging in the slot in said member, a rocking bar mounted on said frame and connected by a link to the rocking lever, and a plunger to engage the rocking bar and to rock it about its support thereby to move said member and release the grip of the pincers.
8. In a machine of the class defined, a rocking frame, a pincers-carrying lever pivotally mounted on said frame, means to maintain the free end of said lever normally raised, pincers comprising independently movable jaws having depending converging shanks carried by said lever, a slotted link operatively connected with said shanks to close the pincers and to move the lever, a rocking bar on said lever in engagement with said link, and a plunger to actuate said rocking bar to open the pincers.
9. In a machine of the class defined, a rocking frame, a lever pivoted at one end on said frame, pincers comprising independently movable jaws having depending converging shanks pivoted on the free end of said lever, means to maintain the free end of said lever and the pincers normally raised, means to determine the highest position of the pincers, and means to close and to open the pincers.
10. In a machine of the class defined, a work support, a rocking frame, a lever pivotally connected at one end to said frame and adapted for movement at its free end towards and from the support, means to move the lever normally towards the support, pincers on said lever, a rocking bar on said lever, a second rocking bar on the frame, and means operating through said rocking bars to actuate the pincers.

CHARLES MARTIN BAGSHAW.
